UNITED STATES PATENT OFFICE

91,133

DESIGN FOR A TOY

Charles Fehrenbach, Mount Vernon, N. Y.

Application October 20, 1933. Serial No. 49,525

Term of patent 7 years

To all whom it may concern:

Be it known that I, CHARLES FEHRENBACH, a citizen of the United States, residing at Mount Vernon, in the county of Westchester and State of New York, have invented a new, original, and ornamental Design for a Toy, of which the following is a specification, reference being had to the accompanying drawing, forming part thereof.

I claim:—

The ornamental design for a toy as shown.

CHARLES FEHRENBACH.
